UNITED STATES PATENT OFFICE

JULIEN PIETERS, OF PARIS, FRANCE

LIQUID-SEAL CLOSURE DEVICE FOR VERTICAL DISTILLATION RETORTS

Application filed March 20, 1928, Serial No. 263,169, and in France March 30, 1927.

The present invention relates to a liquid-seal closure device for vertical distillation retorts, consisting of a trough or gutter of quadrangular shape, delimiting the discharge opening and enclosing water constituting the liquid seal, into which there dips the downwardly-directed flange of a basin adapted to move in the manner of a slide valve with horizontal movement under the action of a pull exerted upon one of its ends, this slide valve being able to travel at its other end over inclined planes so as to be raised progressively, to be freed from the trough or gutter, to take up a horizontal position and to uncover the discharge opening by its further horizontal displacement.

A hopper, delivering in front of this discharge opening, is continued downwardly, upon the side where the slide valve is to lift, by a door adapted to oscillate and to slide vertically when the slide valve is lifted in order to come into a horizontal position, in such a way as to close the gap formed at the base of the hopper and necessary for the lifting movement of the slide valve.

This liquid-seal closure device may be combined with a device for retaining the material contained in vertical retorts for the distillation of coal or other combustible material, such as lignite, peat, bituminous shales, etc. This device has for its object to reduce to the minimum the force necessary for its operation and to economize the material by preventing any crushing during its closure.

For this purpose the distillation chamber is extended at its lower end by a gullet which comprises upon one of its sides a curved wall presenting in section the shape of a circular arc, while it is open upon the other side, facing which there is pivoted, upon the supporting base of the distillation chamber, a flap having the shape of a basket, comprising a curved bottom which presents in section the shape of a circular arc of the same centre as that of the opposite end wall of the distillation chamber,—this bottom of the flap being adapted to place itself in prolongation of the curved surface constituting this wall for a distance such that the material rests upon this wall and upon this flap according to its nat-

ural angle of slope, whilst in order to effect the discharge from the distillation chamber, it suffices to tilt this flap in such a way as to produce its partial or total effacement behind the end wall of the gullet.

The accompanying drawings represent by way of example one form of carrying out the material-retaining device and the liquid-seal closure device.

Figure 1 is a view in vertical section, along the line 1—1 of Figure 2, and

Figure 2 is a view in vertical section at 90° with reference to the foregoing that is to say along the line 2—2 of Figure 1.

Each of the chambers *a* of the distillation chamber is extended, at its base, by a gullet *b*, comprising upon one of its sides a curved wall *b*¹, which presents in section the shape of a circular arc; the other side of this gullet is open, the plane of this opening *b*² being slightly inclined to the vertical, in such a way that the material sliding over the curved wall has a tendency to escape from the gullet through this opening under the action of gravity.

Upon the supporting frame *c* of the distillation chamber, facing this opening *b*² of the gullet, there is pivoted at *d*² a skip or flap *d* presenting the shape of a basket, of which the bottom *d*¹ is curved and presents in section the shape of a circular arc having the same centre as the curved wall *b*¹ of the gullet; the pivot or axis of articulation *d*² of this flap is arranged laterally with regard to the chamber *a* of the distillation chamber, in such a way as not to prevent its clearing at the moment of opening. The lateral cheek plates *d* of this flap are arranged parallel to and externally of the corresponding walls *b* of the gullet. A lever *e*, keyed upon one of the ends of the axis of articulation *d*² of the flap, allows of operating the latter.

In the position represented in the drawings, the bottom *d*¹ of the basket *d* is situated in prolongation of the curved wall *b*¹ of the gullet *b*, which this bottom thus continues up to a certain distance beyond the vertical plane passing through the upper part of the opening *b*² of the gullet. The material contained in the distillation chamber *a* thus

rests, according to its natural angle of slope, upon the surface of the curved wall b^1 of the gullet and upon the bottom d^1 of the skip or basket; the latter must be raised more or less 5 considerably, according to the angle of this slope.

In order to effect a more or less partial discharge of the distillation chamber a , it suffices to move back the flap d d^1 more or less 10 behind the gullet b , the bottom d^1 of this basket thus placing itself beneath the curved wall b^1 —, by actuating the operating lever e by hand.

The latter might likewise be actuated mechanically. This retaining device is preferably placed in the direction of the largest dimension of the distillation chamber, that is to say that the axis of articulation d^2 of the basket or skip d d^1 is arranged along a direction parallel to the direction of length of the distillation chamber.

It is easy to understand that the flap, during its movement for returning to the position for retaining the material from its position of effacement, cannot grind or crush the material to be discharged, because this movement serves only to create a surface for supporting the material according to its natural slope, that is to say without the flap striking 30 against a surface of any kind.

The material, passing through the opening b^2 of the gullet uncovered by the bottom d^1 of the basket d , falls into a hopper f ; below and externally of the latter, there is arranged 35 a box or caisson g provided at its lower part with a trough or gutter g^1 of rectangular shape which defines an opening in the bottom of the box, containing up to a certain level, water intended to provide a liquid seal. This 40 trough or gutter delimits the discharge opening. Into this gutter g^1 there dips the downwardly directed flange h^1 of an inverted basin h ; the latter comprises, along its longer sides, cheek plates h^2 directed upwardly, 45 upon which are journaled, externally of the basin h , two pairs of rollers i ; these rollers can run upon rails i^1 fixed to the walls of the caisson g , above the gutter g^1 , along the longer sides of the latter. These rails are horizontal 50 for the greater part of their length; near one of their ends, above the small sides of the gutter g^1 , they comprise inclined planes i^2 .

The basin h is connected, at the opposite end, to a rod h^3 , having a handle h^4 ; when, 55 by means of the latter, a pull is exerted upon the basin h , the latter can travel in the manner of a slide valve; at the start of its movement, the rollers i rising upon the inclined parts i^2 of the rails i^1 , will produce at first a 60 gradual lifting of the slide valve basin h , until the flange h^1 is lifted completely above the upper edge of the gutter g^1 and the slide valve basin h comes to occupy a horizontal position. By continuing to pull by the handle h^4 upon the slide valve h , the latter is dis-

placed horizontally by means of the rollers i upon the rails i^1 until the slide valve completely uncovers the discharge opening delimited by the trough or rectangular gutter g^1 ; the slide valve h takes up a position in 70 the lateral prolongation g^2 of the caisson g , which possesses dimensions sufficient to receive the slide valve in its open position.

At the base of the hopper f , facing the lower extremity of the slide valve basin in the 75 closed position, there is arranged a door k , suspended in such a way as to be able to oscillate upon a horizontal spindle k^1 in guides k^2 fixed to the lower part of the hopper f ; this door k can oscillate and travel vertically in 80 these guides k^2 when the slide valve h lifts in rising upon its rollers i over the inclined planes i^2 of the rails i^1 . This door prevents the fall of material beyond the basin h , while allowing the vertical movement of the latter, 85 for the height necessary to free it from the gutter g^1 forming the hydraulic seal; this door k falls again by its own weight when the slide valve h is pushed back, by means of the rod h^3 h^4 , into the closed position in which 90 the slide valve basin returns to engage in the interior of the gutter g^1 , descending by means of the rollers i along the inclined planes i^2 .

Water is brought into the gutter, forming 95 a liquid seal, by a fitting g^3 connected to the water pipe; drain pipes g^4 , connected to the base of the caisson g , g^1 , g^2 , allow the cleaning of the latter.

This arrangement of liquid seal insures a 100 very gas-tight closure preventing any entrance of air, which is a condition difficult to fulfil for vertical distillation retorts, generally of great height.

What I claim is:

1. In a liquid seal closure device for a vertical retort having an open bottom for the distillation of combustible material, the combination of a casing having an open bottom, fixed in spaced relation under and adjacent the opening in the bottom of the retort and communicating with the latter by means of the open top of said casing, a trough of quadrangular shape provided around the open bottom of said casing so as to provide a container for a body of water, a basin constituting a slide valve mounted for sliding horizontal movement within said casing and said basin having portions projecting into said trough adapted to be seated in said water to form a liquid seal.

2. In a liquid seal closure device for a vertical retort having an open bottom for the distillation of combustible material, the combination of a casing arranged under and adjacent the openings in the retort, a trough of quadrangular shape located at the bottom of said casing, said trough delimiting the discharge opening in said casing and constituting a container for water, the inner walls 125

of the trough defining an opening in the bottom of the casing, a basin mounted for horizontal sliding movement within said casing serving as a slide valve, a downwardly directed flange along the edges of said basin projecting into the water contained in said quadrangular trough, stationary inclined tracks secured to said casing upon which said slide valve basin may travel in order to raise or lower said downwardly directed flange upon said basin from or into the water in said trough to serve as a liquid tight seal closure.

3. In a liquid seal closure device for a vertical retort having an open bottom for the distillation of combustible material, the combination of a casing having an open bottom fixed in spaced relation under and adjacent the opening in the bottom of the retort and communicating with the latter by means of the open top of said casing, a trough of quadrangular shape located at the bottom of said casing delimiting the discharge opening and constituting a container for water, a basin mounted for horizontal sliding movement within said casing functioning as a slide valve, a downwardly directed flange under the edges of said basin designed to tip into the water contained in said quadrangular trough, rollers secured to said basin, rails secured to the casing above said trough and extending horizontally along the sides of said trough, said rails having at one end thereof an inclination whereby upon movement of said rollers upon said inclination said slide valve basin will raise or lower said flange from said trough to form a liquid tight closure.

4. In a device as claimed in claim 1, a hopper located above said slide valve basin having an opening directed towards the discharge opening in said casing and a door carried at the lower end of said hopper pivotally mounted so as to oscillate and to slide vertically when the slide valve basin is raised from the trough.

In testimony whereof I have signed my name to this specification.

JULIEN PIETERS.
